ROTATABLE MERCHANDISE DISPLAY RACK

Victor Kurtz, 60 W. 57th St., New York, N.Y.

Filed May 25, 1964, Ser. No. 80,122

Term of patent 7 years

(Cl. D80—10)

FIGURE 1 is a top plan view of a rotatable merchandise display rack, showing my new design;

FIG. 2 is an elevational view, and

FIG. 3 is an enlarged top perspective view thereof.

I claim:

The ornamental design for a rotatable merchandise display rack, substantially as shown.
